UNITED STATES PATENT OFFICE.

CHARLES A. CLARK, OF HARTFORD, CONNECTICUT.

SWITCH-BUTTON.

No. 889,871.

Specification of Letters Patent. Patented June 3, 1908.

Original application filed October 24, 1907, Serial No. 398,887. Divided and this application filed February 15, 1908.
Serial No. 416,147.

To all whom it may concern:

Be it known that I, CHARLES A. CLARK, a citizen of the United States, and a resident of Hartford, in the county of Hartford and State of Connecticut, (whose post-office address is 62 Maple avenue, Hartford, Connecticut,) have invented certain new and useful Improvements in Switch-Buttons, of which the following is a full, clear, and exact description, whereby any one skilled in the art may make and use the same.

The invention relates to buttons for switches and more directly to a button having a resilient connection with features of automatic adjustment.

The objects of the invention are to provide a simple and effective means for securing a proper adjustment between the button of the switch and the face plate or cover and the spindle thereof.

A further object is to produce a button having its contained resilient parts so arranged that there will be practically no liability of relative rotation between the button and said parts.

A still further object is to provide an adjustable button having a resilient cushion of extreme simplicity and one which is not liable to lose its effective tension in use.

Referring to the drawings: Figure 1 is a view illustrating a button applied to a rotary snap switch and with parts broken away in section to better illustrate the construction. Fig. 2 is an enlarged side view illustrating the retainer and its several appurtenant parts. Fig. 3 is a section view taken on the line x—x of Fig. 2.

The button hereinafter described is particularly designed for and is used in connection with switches and may be applied either to a rotary snap switch such as illustrated or to what is commonly known as a flush switch. In either case there is usually a spindle for actuating the switch mechanism which extends through, or adjacent to an opening in the plate or cover which incloses or covers the working parts. The button is screwed or otherwise secured to the spindle and is used for rotating same.

It has been found desirable and necessary to provide some means appurtenant to the

button for permitting a close fit of said button with reference to the face plate or cover without liability of undue cramping.

It is the primary object of the present invention, to provide a button having a resilient cushion interposed between the button and its means for attachment to the spindle. It is also intended to arrange the resilient cushion in such form that it will maintain its spring action and will not be liable to lose its resiliency.

In the accompanying drawings the numeral 1 denotes the button applied to the spindle 2 which, as shown herein extends through the cover 3 of the snap switch 4. The switch forms no part of the invention and its details have not therefore been illustrated, although it is to be understood that the spindle 2 upon rotation of the button 1 actuates the switch mechanism.

The button 1 is composed of any desirable material, preferably one, which may be molded, vulcanized, or otherwise employed to surround and hold a suitable retainer 5. This retainer 5 is substantially cylindrical in form and is provided with a header 6, opened sides 7 and 8, and side frame members 9 and 10. The side frame members 9 and 10 normally extend below the lower end 10^a of the button 1 and are arranged to pass through and be bent over a washer 11. This washer 11 is notched on opposite sides, and the ends 12 and 13 are passed through the notches and then bent inward over the plate or washer 11.

The retainer 5 is arranged to be secured in the body of the button in any desired manner as by molding it therein or otherwise securing it, and forms a suitable recess for the spring cushion and appurtenant parts.

Within the recess of the retainer there is located a spring plug 14, which has, at its inner end a head 15, corresponding in general form to the inner walls of the retainer. This spring plug is provided with a screw threaded socket 16 at its lower end by which it may be engaged with the threaded spindle of the switch.

The body part of the spring plug is preferably of angular cross section and upon it are arranged a series of leaves 17, having perforations corresponding in shape to the body

part of the spring plug 14. As shown herein these spring leaves are arranged in pairs with their curvature opposed to each other, so that each pair of leaves thus arranged form a spring member of substantially elliptical form. To secure greater ease of action between the opposed spring leaves, bearing plates 18 are interposed between them and thus the two semi-elliptical leaves bear upon opposite sides of the bearing plates 18. It will thus be seen that the spring cushion between the header 15 and the washer 11 is made up of a series of elliptical springs, and of course, it is apparent that the intermediate bearing plates 18 may or may not be used as desired.

By having the spring leaves and the spring plug of angular form, there is little or no possibility of any of the parts rotating relatively to each other and as they are all held within an inclosed retainer, there is practically no opportunity for the parts cramping or wearing.

The invention herein described is similar to an invention forming the subject matter of a co-pending application. The particular invention herein shown and described being

matter divided from said co-pending application. Ser. No. 398,887, filed Oct. 24, 1907.

What I claim as my invention and desire to secure by Letters Patent is:

1. A switch button having a recess, a spring plug located therein, curved spring leaves arranged in pairs and with their curvatures opposed and means for retaining said spring leaves within the recess.

2. A switch button having a recess, a spring plug located therein, curved spring leaves arranged in pairs and with their curvatures opposed, bearing plates intermediate the said opposed spring leaves, and means for retaining said leaves and bearing plates within the recess.

3. A switch button having a recess, a spring plug located therein, a plurality of spring members of substantially elliptical form arranged upon said spring plug and means for retaining said spring members within the recess.

CHARLES A. CLARK.
